UNITED STATES PATENT OFFICE.

JOHN HOEY, OF SAN FRANCISCO, CALIFORNIA.

BED-BOTTOM ATTACHMENT.

SPECIFICATION forming part of Letters Patent No. 696,239, dated March 25, 1902.

Application filed July 24, 1901. Serial No. 69,470. (No model.)

To all whom it may concern:

Be it known that I, JOHN HOEY, a citizen of the United States, residing in the city and county of San Francisco, State of California, 5 have invented an Improvement in Bed-Bottom Attachments; and I hereby declare the following to be a full, clear, and exact description of the same.

My invention relates to an attachment 10 which is designed for use in connection with woven-wire and similar mattresses or "bed-bottoms," as they are termed.

It consists in a combination, with the wooden side bars of such a mattress or bed-bottom, of 15 an adjustable and reversible plate and lug which is designed when in its normal use to retain the bed-bottom frame in position upon a bedstead-frame, and its other use is as a protection for the ends of the side frames to 20 prevent their being split and damaged in transportation.

Referring to the accompanying drawings for a more complete explanation of my invention, Figure 1 is a transverse section of one 25 of the side frames of the bed-bottom and of the bedstead-rail, showing the application of my attachment. Fig. 2 is a perspective view showing it in position as a protector.

Bed-bottoms of the class referred to are composed of side bars A, which are united by 30 transverse end bars bolted to them, and a woven-wire-mattress fabric is stretched between the end bars, forming an elastic surface to support the usual hair or other mattresses which are placed thereon. The width 35 of the mattress is such that in the present construction the side bars A rest upon the top of the side rails B of the bedstead-frame, and my invention or attachment is designed 40 to prevent the bars A from slipping off the rails B to one side or the other. It consists of a plate 2, having at one end a lug 3, turned at right angles with the surface of the plate 2. Within the plate 2 is formed a longitudinal slot 4, through which the screw 5 passes and by which the plate is secured to the bar A. The length of the slot 4 allows of sufficient adjustment, so that any little discrepancy between the width of the bed-bottom 45 and the width of the bedstead-frame can be compensated. Thus when the plates 2 have been screwed to the bars A, one near each

end of each of the bars, the lugs 3 are adjusted, so that the sides of the bedstead-frame B may lie between them, the lugs overlapping these sides, and the screws being tightened the bars A will be supported upon the rails B, the lugs 3 preventing any side movement.

It will be understood that the plates 2 may 60 be secured so that the lugs 3 either extend upon the outside or upon the inside of the rails B, as may be desired.

This class of bed-bottoms are usually manufactured in quantity in the shops and are then 65 shipped to the various parts of the country to fill orders.

The ends of the side bars A are usually unprotected on the lower angles, so that if they are accidentally hit against anything in moving they are apt to be split off. The upper sides of these bars A are protected by the transverse end bars, which are bolted to them close to the ends. In order to protect these lower angles, the plates 2 are reversed and 70 turned at right angles with their normal position, so that the hook-lugs 3 project over the lower angles of the bars A, and thus prevent any contact with steps or stones while they are being moved from place to place. 75 When they have been received and are ready to set up, it is only necessary to reverse the plates 2, turning them at right angles with the length of the frame, and the device will be in readiness for use.

Having thus described my invention, what I claim, and desire to secure by Letters Patent, is—

1. A bed-bottom frame including side and end bars, said side bars adapted to rest directly 90 upon the upper edges of the bedstead-rails, in combination with a flat plate adjustably secured to the bottom surface of said side bars and extending crosswise thereof, said plate having a lug at one end to hook over the upper angle of an underlying bed-frame rail whereby the bed-bottom frame is held against side-movement on the bed-frame.

2. A bed-bottom frame including side and end bars, said side bars adapted to rest directly 100 upon the upper edges of the bedstead-rails, in combination with a flat plate fitted directly to the under side of each of the side bars and adapted to lie between said under side and

the upper edge of the bedstead-rails, and extending transverse thereof and having a downturned lug at its outer end, said plate removably secured and capable of reversal 5 whereby it may extend lengthwise of said end bar and its lug portion may project in an opposite direction and engage and protect the edge of the side rail.

3. A bed-bottom frame including side and 10 end bars said side bars adapted to rest directly upon the top edges of the bedstead-rails and having secured directly to their under surface a transversely-extending hook-shaped

member the hook whereof projects beyond the vertical plane of the outer sides of the 15 side bars and also the bedstead-rails whereby it may engage the upper angle of the bedstead-rail of a bed-frame and hold the bed-bottom from against lateral movement on the bed-frame.

In witness whereof I have hereunto set my hand.

JOHN HOEY.

Witnesses:

CHARLES F. HOEY,
FRANK TWICHELL.
